J. G. KNAPP.

PRIMARY IGNITION CIRCUIT BREAKER.

APPLICATION FILED JULY 8, 1916.

1,294,678.

Patented Feb. 18, 1919.

UNITED STATES PATENT OFFICE.

JOSEPH G. KNAPP, OF OMAHA, NEBRASKA.

PRIMARY IGNITION CIRCUIT BREAKER.

1,294,678.

Specification of Letters Patent. Patented Feb. 18, 1919.

Application filed July 8, 1916. Serial No. 108,168.

To all whom it may concern:

Be it known that I, JOSEPH G. KNAPP, a citizen of the United States, residing at Omaha, in the county of Douglas and State 5 of Nebraska, have invented certain new and useful Improvements in Primary Ignition Circuit Breakers; and I do hereby declare the following to be a full, clear, and exact description of the invention, such as will 10 enable others skilled in the art to which it appertains to make and use the same.

This invention relates to circuit breakers, and has for its primary object to provide a device of this character which, when applied 15 in the primary circuits of an engine ignition system, may be operated to either open or close the circuits.

Another object of the invention is to provide a circuit breaker designed to be applied 20 in the primary circuits of an engine ignition system, between the induction coils and the commutator, whereby the said circuits may be opened or closed at will.

A further object of the invention is to provide a circuit breaker of the above stated 25 character embodying a lock, whereby the device may be locked in an open or closed position.

With these and other objects in view, as 30 it will appear as the description proceeds, the invention comprises the various novel features of the construction, combination and arrangement of the parts as will be more fully described hereinafter and set 35 forth with particularity in the appended claim.

Referring to the drawings,

Figure 1 is a perspective view showing the manner in which my improved circuit 40 breaker is attached to the ordinary coil box.

Fig. 2 is a side elevation of the breaker box with the cover removed, with parts of the casing end walls being broken away.

Fig. 3 is a vertical transverse sectional 45 view on the line 3—3 of Fig. 2.

Fig. 4 is a diagrammatic view showing the arrangement of my improved circuit breaker in the primary circuits extending from the induction coils to the commutator.

In carrying out the object of the present 50 invention, I desire to have it understood that this circuit breaker may be employed in connection with the primary wires of any engine ignition system, but for the sake of 55 convenience and the purpose of illustration,

I will describe the device as being used in connection with the primary circuits of an ordinary four-cylinder automobile ignition system.

Referring more particularly to the drawings, the reference letter A indicates the casing or box in which my improved circuit breaker is inclosed, this box being attached to the coil box B in any suitable manner, as will be clearly seen by reference to Fig. 1. 60 This casing A comprises end walls 1 and 2, bottom and top walls 3 and 4, respectively, and a rear wall 5. The end wall 1 is provided with a right angular flange 6 which extends laterally in spaced relation to the side edges of the upper and lower walls 3 and 4. A right angular flange 7 extends inwardly and laterally from the end wall 2 and is provided with slots 8, the purpose of 65 which will presently appear.

A suitable cover 9 having right angular flanges 10 is used to close the casing, the flanges 10 overlapping and bearing upon the upper and lower walls 3 and 4 of the casing, while the forward edge of the door being designed to engage both the flange 6 and the side edges of the upper and lower walls of the casing. The opposite end of the cover 9 is provided with a reinforcing strip 11 that extends vertically and is provided with hooks 12 which are adapted to be passed through the openings 8 whereby they may be locked in order to hold the cover securely upon the casing. 70

The casing is further provided with openings 13 to permit of the entrance and exit of the primary wires into the casing. The rear wall 5 is provided with a plurality of openings 14 through which suitable fastening means are adapted to be passed in order 75 to secure the casing upon the coil box B, or any other suitable support that may be found desirable.

A pin tumbler cylinder 15 having a reduced threaded extension 16 is threadededly 80 connected through the end wall 1 and securely held in position by a retaining nut 17 threadededly connected to the end 16 and bearing against the inner face of the wall 1. This tumbler cylinder 15 embodies a key 100 barrel 18, which latter carries a cross head 19, the latter being connected to a rotatable shaft 20 that is formed of any suitable insulating material. A rod 21 is connected to the cross head 18 and extends through the 105

2
rotatable shaft 20 and is journaled in the end wall 2 of the casing so as to permit of the shaft 20 being revolved when the key barrel 18 is revolved. As clearly shown in Figs. 1 and 2 of the drawings, a suitable key 22 is used to rotate the barrel 18. This shaft 20 is mounted eccentrically on the rod 21 and is provided circumferentially with a plurality of grooves 23 arranged in spaced relation to each other and which are designed to receive and hold in spaced relation, spring contact arms 24. Each of these spring contact arms 24 is provided with a horizontal angular extension 25 which rests against and is secured to a strip of insulating material 26 securely fastened to the under face of the upper wall 4.

Threaded studs 27 extend downwardly from this insulating strip 26 through apertures in the angular extensions 25 of the arms 24, and are each provided with a retaining nut 28 designed to securely hold and retain the arms 24 against the insulating strip 26. A thumb nut 29 is threadedly connected to each of the studs 27, whereby the terminal ends of the primary wires leading from the induction coils may be attached and securely held in place on the studs between the nuts 28 and the clamping nuts 29. Arranged on the inner upper face of the lower wall 3 and extending longitudinally of the casing is an insulating strip 30 on which is arranged a short circuiting bar 31, this bar extending longitudinally of the casing and arranged below the rotatable shaft 20 adjacent the lower ends of the spring arms 24. The opposite ends of the bar 31 are provided with ears 32 whereby the bar may be securely fastened upon the insulating strip 30 by any suitable means, such as screws 33.

Arranged adjacent the bar 31 upon the insulating strip 30 are a plurality of spaced upright contacts 34, each of which is arranged on a threaded stud 35 and is held in place by a suitable clamping nut 36. Clamping nuts 37 are threadedly connected to the ends of the studs 35 whereby the terminal ends of the primary wires may be connected leading from the commutator, which latter is grounded upon the engine.

In the operation of the device, and when the key 22 has been inserted into the tumbler cylinder, the key is rotated to the right, which in turn rotates the shaft 20, forcing the spring contact arms 24 outwardly into contact with the stationary contacts 34, so as to complete the circuit through each and all of the primary wires leading from the induction coils to the commutator. When the key is rotated to the left, the eccentric shaft 20 will be rotated to permit the spring contact arms 24 to move away from the stationary contacts 34 into engagement with the short circuiting bar 31. From this it

will be seen, and by reference to the diagrammatic view, Fig. 4, that when the primary circuits are broken, the current will pass from the magneto 37 to the bus bar 38 of the induction coils 39, where it will pass through the primary wires 40 to the spring contact arms 24, thence to the short circuiting bar 31.

When the shaft 20 has been rotated to the right so as to move the contact arms 24 into engagement with the contacts 34, the current will pass from the magneto 37 through the induction coils in the respective firing order through the primary wires to the contact arms 24, through the contacts 34, and the primary wires 41 extending therefrom to the commutator 42, where the current is grounded, thus making a complete engine circuit.

From the foregoing, it will be apparent that when the shaft 20 has been rotated to the left to short circuit the primary circuit wires, and the key 22 removed it will be impossible for any one to bridge a wire or wires from the commutator 42 over the circuit breaker to the induction coils 39 in order to start the engine.

In the event that some one should tamper with the ignition system and try and start the motor, and we will say for the purpose of illustration, by bridging a wire from No. 1 induction coil over the circuit breaker to the contact 1 of the commutator, it will be manifest that current will flow from the magneto 37 through the bus bar 38, induction coil 1, through the bridged wire to the contact 1 of the commutator and then to the ground, to fire cylinder No. 1, it being understood that the cylinders are arranged in circuit with and in firing order with the induction coils. From this it will be seen that at the same time cylinder No. 1 is firing, the current will pass through induction coil No. 2, primary wire 40, contact arm 24, short circuiting bar 31, through contact arm 24, primary wire 40 to induction coil 1, where the current will pass over the bridged wire to contact point 1 of the commutator and thence to the ground, thus firing cylinder No. 2. Each of the remaining cylinders 100 will consequently be fired in the same manner. Therefore from the above description, 110

it will be apparent that any attempt to bridge the induction coils with the commutator by connecting them directly over the circuit breaker will result in the firing or the 120 sparking of all of the spark plugs of the engine cylinders at the same time, thus producing an ignition system which will positively be inoperative.

Arranged against the inner face of the end wall 2 is a plate 43 vertically movable between the end wall 2 and a bracket 44 which extends vertically over the plate 43 and is secured to the end wall 2. This plate 125

43 carries lugs 45 which are designed to lockingly engage both the hooks 12 carried by the door 9.

Arranged below the plate 43 and secured 5 to the end wall 2 is a spring arm 46, the outer end of which exerts an upward tension against the lug 47 on the plate 43. When this plate 43 is moved downwardly to disengage the lugs 45 from beneath the hooks 10 12, the spring arm 46 will return the plate 43 carrying the lugs 45 upwardly to its normal position.

Mounted on the end of the rod 21 and bearing against the end of the rotatable shaft 20 is an arm 48 which is held to rotate with the rod by a clamping nut 49. When the shaft 20 is rotated to the left, this arm 48 will come in contact with a lug 50 on the plate 43, and by a continued movement of the shaft 20 and the arm 48 to the left, the lug 50 will be forced downwardly sufficiently to move the lugs 45 from beneath the hooks 12, whereby the cover may be readily and quickly removed from the casing.

25 The plate 43 is provided with a slot 51 which extends vertically upward from its bottom and is designed to receive the end of the rod 21.

A slot 52 extends vertically of the plate 30 43 and has arranged therein a block 53

which is secured to the lower end of the bracket 44 by a screw 54.

From the foregoing description taken in connection with the accompanying drawings, the advantages of construction and 35 the method of operation of the invention, together with the device which I now consider to be the best embodiment thereof, will be readily understood by those skilled in the art to which the invention relates, and while I 40 have described the principle of the operation of the device, I desire to have it understood that such changes may be made when desired as are within the scope of the appended claim. 45

What I claim is:—

In an engine ignition system, the combination with the induction coils thereof, a commutator, primary wires connecting the induction coils with the commutator, and a circuit breaker arranged in the primary wires between the induction coils and the commutator.

In testimony whereof I have signed my name to this specification in the presence of 55 two subscribing witnesses.

JOSEPH G. KNAPP.
